Application February 26, 1949, Serial No. 78,605

14 Claims. (Cl. 237—9)

1

This invention relates to heat-exchange systems employing steam for processing materials, such as steam systems in laundries, paper mills, and other industries.

The present application is a continuation-in-part of our abandoned application Serial No. 762,628, filed on July 22, 1947, and our abandoned application Serial No. 764,454, filed on July 29, 1947. The two prior disclosures, as far as is consistent herewith, are incorporated in the present disclosure by reference.

Other copending applications disclosing the subject matter related hereto are: S. N. 78,842, filed February 28, 1949; S. N. 78,843, filed February 28, 1949; S. N. 78,604, filed February 26, 1949; S. N. 80,802, filed February 28, 1940; and S. N. 777,894, filed October 4, 1947.

A steam system of the type here under consideration may be termed a "clear channel" system, meaning that a clear channel (no traps) exists from the boiler through the equipment to the return line. Such a clear channel makes the whole system "responsive" in the sense that a drop in pressure at the end of the return line causes an immediate velocity response throughout all the equipment. This fact is important because it makes possible velocity control for the whole system at a single point at the end of the return line.

It is old to create such a pressure differential and consequent velocity response solely by opening a valve at the end of the return line, as disclosed in Patent 2,366,332 issued to Harrison et al., the released fluid being utilized to preheat and deaerate make-up water for the boiler. But while such a valve arrangement used alone is highly effective and has been commercially successful, nevertheless in some situations it presents certain problems in economy and efficiency, which problems, we find, can be solved by adding other ways of promoting velocity and utilizing steam at the return end of the system.

The broad object of the present invention is to provide such solutions by certain actions at the end of the return line. One such action is the removal of condensate under pressure from the return line above the release valve for direct return to the boiler. This action of course has a flow-promoting effect on the responsive clear channel system. Another action is the condensing of steam in the return line above the release valve. This action, too, supplements the flow-promoting effect of the release valve and in addition consumes steam in the return line. Other actions include cooling actions taking place in a

2

receiver at the end of the return line, the release valve being adapted to open in response to such cooling. These various actions are combined with the action of the release valve in various ways in various practices of the invention.

An important object of the preferred form of the invention is to achieve a new and novel return system having the advantages of an "open" system combined for the first time with the advantages of a closed system.

When all the returns from the equipment of a steam system pass through the release valve at the end of the return line and thus drop to substantially atmospheric pressure, as disclosed in 15 the Harrison et al. patent, the return system is termed an open system. The outstanding advantage of an open system is the availability of maximum pressure differential to create flow through the equipment. This maximum differential is the full difference between boiler and atmospheric pressure.

One disadvantage of an open system is that bringing all of the returned condensate down to 20 atmospheric pressure causes a substantial portion to flash into steam. It is difficult to salvage the B. t. u.'s of the flash steam and usually they are entirely lost to the atmosphere.

Another disadvantage of an open system is the 25 low temperature of the condensate returned to the boiler, since the maximum possible temperature of condensate at atmospheric pressure is 212° F.

A closed system, on the other hand, in which the condensate is kept under pressure, has the 30 advantage of avoiding flashing losses as well as the advantage of returning condensate at high temperature, say around 300° F. in a system operating at 100 p. s. i. g. (pounds per square inch gauge pressure).

As will be explained more fully, the preferred 35 practice of the present invention combines the advantages of open and closed systems by removing the condensate from the return line above the release valve under pressure for direct return to the boiler. Thus flash losses are 40 eliminated and the condensate reaches the boiler at a high temperature characteristic of closed systems. Independently of this action, the release valve is free to set up whatever pressure 45 differential may be desired just as in open systems.

A further object of the preferred practice of 50 the invention is not only to promote velocity in the system by pressure drop at the end of the return line, but also to deliver the make-up water

to the boiler at a higher temperature than possible in any conventional steam system. This dual object is accomplished by transferring heat from the return line to the make-up water as the make-up water travels from the usual feed pump to the boiler. Thus the make-up water causes condensation in the return line to promote flow velocity in the system and at the same time is itself raised to a high temperature on the order of 300° F. It is possible to heat the make-up water to this high temperature and to do so without creating any pumping problem because the additional heating occurs on the discharge side of the feed pump where the water is under high pressure.

These and other objects and advantages of our invention will be apparent from the following detailed description taken with the accompanying drawings.

In the drawings, which are to be considered as merely illustrative:

Fig. 1 is a front elevation of a typical embodiment of the invention as a self-contained master control unit;

Fig. 2 is a diagram of a representative steam system incorporating the new control unit; and

Fig. 3 is a similar diagram illustrating a modified form of the invention.

Fig. 1 illustrates how the invention may be embodied in a piece of apparatus that may be manufactured as a self-contained unit for installation in steam plants, usually in the boiler room. This form of the unit includes an upright tank or receiver 10 and a housing or casing 11 associated therewith. The housing may completely enclose the tank or may, as in the present construction, extend forward from the tank to provide an enclosed space for the numerous elements that make up the control combination. The casing may be of sheet metal construction with upper and lower sliding doors 12 that may be opened for access to the interior. The casing includes a panel-board 13 on which are various indicating devices that will be described later.

Fig. 1 shows five important pipes connected to the master control unit, the purpose of which pipes will be readily understood from the description below of Fig. 2. These five pipes are: a pipe 15 for supplying new water to the unit; a pipe 16 connected to the discharge side of the usual boiler feed pump; a pipe 17 which is the boiler feed line for supplying water to the boiler; the return line 18 of the steam system and, at a lower level, the pipe 20 to the intake side of the boiler feed pump. If desired, an additional vent pipe 21 may be connected to the vent opening of the tank 10.

Fig. 2 shows diagrammatically the principal elements of a steam system including the important parts of the new master control unit. The parts of the unit itself are shown inside a rectangle 22 indicated by a broken line in Fig. 2. Everything inside this rectangle in Fig. 2 is inside the casing 11 of the unit shown in Fig. 1.

In the system shown in Fig. 2, steam from a boiler 23 is supplied through a header 25 to a plurality of equipment heat exchangers or steam-using devices 26. Such devices may be, for example, the various machines in a laundry or the drying equipment used in paper manufacture, plastics, etc. Return pipes 27 from the various pieces of equipment connect with the previously mentioned return line 18.

Instead of traps, each of the return lines 27 is provided with a suitable restriction such as a

nipple 28 of relatively small diameter. It will be noted that in such an arrangement there is a clear channel of open communication from the return line 18 back through the various pieces of equipment 26 to the boiler so that lowering pressure in the return line 18 will cause velocity responses in each of the steam-using devices. Thus steam flow through all the equipment may be controlled from one point at the end of the return line.

The return line 18 may be terminally connected to the side of a steam separator 31 which preferably, but not necessarily, also serves as a heat exchanger for using the returned condensate to heat new makeup water. The combined heat exchanger and separator 31 is shaped and dimensioned to permit the condensate to separate from the steam and, if desired, suitable baffles 32 may be added to facilitate such separation.

The condensate that is separated from the steam gravitates through a pipe 33 to the intake side of a condensate pump 35 that is included in the working parts of the master control unit. The pump 35 discharges the condensate upward through a pipe 36. Preferably, the pump operates continuously. A valve 37 is provided in the pipe 33 to cut the heat exchanger off from the pump if desired.

A pipe 38 conducts fluid from the return line 18 into the receiver tank 10 and for that purpose is connected to the side of the separator 31. Inside the receiver tank 10, the pipe 38 leads to a two-stage combined heater and mixer 48 which in turn communicates with a spray head 41. The thermostat control is such that the valve 42 opens in response to decrease in temperature of the thermostat bulb 43 and closes in response to increasing temperature of the bulb. The critical temperature at which the valve opens and closes may be varied by virtue of a manual adjustment 45 on the thermostat valve 42.

The combined heat exchanger and separator 31 is, in effect, an extension of the return line and is to be regarded as a part of the return line. Thus the return line ends in the pipe 38 at the thermostatic valve 42. In other words, the combined heat exchanger and separator 31 is in the return line 18 upstream from the thermostatic valve 42.

The steam or steam mixed with condensate that flows through the pipe 38 and the valve 42 enters a central upright passage 46 in the two-stage heater 48 and divides, one portion flowing into an upper jet 47 for the first-stage heating of new water, and the other portion flowing into a lower jet 48 for the second-stage heating. The upper jet 47 is directed into a Venturi throat 50 and the lower jet 48 is directed into a corresponding Venturi throat 51, each jet and throat forming a low-pressure space for the introduction of fluid.

New water for the steam system from the previously mentioned supply pipe 15 passes through a float-controlled valve 52 and through a vent condenser 53 to a pipe 55 that enters the two-stage heater 48 in the low-pressure space between the first jet 47 and Venturi throat 50. The resulting mixture flows through a lateral connecting passage 56 into the low-pressure space between the second jet 48 and second Venturi throat 51, where it is joined by the second portion of hot fluid from the pipe 38. From the two-stage heater the heated water flows into the spray head 41 in heat-exchange relation with the thermostatic bulb 43. The water is not only heated but

is also under considerable pressure in the spray head 41 and is discharged downwardly through the spray ports with considerable violence.

Preferably the tank is maintained slightly above atmospheric pressure, say 3 or 4 pounds above atmospheric pressure. For this purpose, the tank is of closed construction and the vent 21 is provided with both a vent valve 58 and a relief valve 59. The vent valve may be adjusted at a slightly open position to maintain the desired approximate pressure in the tank, and the relief valve 59 may be adjusted to pop off at some higher pressure, say 8 to 10 pounds per square inch gauge pressure.

It is contemplated that the spray capacity of the spray head 41 will be so limited relative to the input of fluid that the pressure in the spray head will rise above the pressure prevailing in the tank 10 when the thermostatic valve 42 is open. Under such conditions, the pressure in the spray head may go substantially above the tank pressure. It is further contemplated that the extent to which pressure will rise in the spray head under given conditions may be varied either by varying the number of spray openings or changing the size of the spray openings.

When the heated water is released in finely divided particles from the spray head 41 into the interior of the tank 10, the water particles are shattered by flashing action and the non-condensable gases are effectively released from the water to escape upwardly through the vent opening 21. The vent condenser 53 not only reclaims heat from the escaping gases but also condenses any vapors that tend to escape with the gases, the recovered condensate dripping to the bottom of the tank.

The tank 10 contains in its lower portion a reserve body 60 of the deaerated make-up water supplied by the above-described spray action. When the level of this body drops, a suitable float 61 opens the previously mentioned valve 52 by suitable mechanical means including an upwardly extending operating rod 62. If the level of the water body 60 rises too high, it overflows through an overflow pipe 63. To prevent the continual release of pressure through the overflow pipe 63, the overflow pipe is provided with a float valve 64 that is normally closed but opens automatically whenever the water level in the tank rises unduly. When desired, the whole water content of the tank may be flushed out by opening a drain valve 66.

The deaerated make-up water, usually at above 212° F. by virtue of the pressure existing in the tank 10, is taken from the tank through the previously mentioned pipe 20 to the intake side of the usual boiler feed pump 67 and is discharged by the pump into the previously mentioned pipe 16 that is connected to the top of the control unit. The pipe 16 is connected to the inlet end of a heat-exchange coil 68 in the previously mentioned combined heat exchanger and steam separator 31. The outlet end of this coil 68 is joined to the previously mentioned pipe 36 from the condensate pump 35 to supply the previously mentioned boiler feed line 17 as indicated in Fig. 2.

Inside the master control unit, means may be provided to divert at least some of the discharge from the boiler feed pump 67 directly into the shell of the combined heat exchanger and separator 31. For this purpose, the pipe in the master control unit that connects with the pipe 16 from the boiler feed pump 67 is provided with a

branch 103 leading to a spray head 104 inside the separator 31, and two manually adjustable valves 105 and 106 are provided as shown to permit variation in proportioning the flow between the coil 68 and the spray head 104.

The feed-water pump 67 may be controlled in a well known manner by means responsive to changes in the water level in the boiler 23 or in some practices of the invention may be manually adjusted to run continuously at approximately the rate required to keep the boiler level constant. In either event, the float 61 in the master control tank 10 will drop periodically to cause new water to be supplied to the system in accord with the boiler demand. Since the boiler demand for make-up water varies with the heat load on the system, it is apparent that the master control unit is responsive to changes in the heat load on the system.

In the preferred practice of our invention the master control unit is provided with special means for introducing pulsations into the steam system in a closely controlled manner. An example of such a means is an intermittently operated water valve 70 in Fig. 2. This valve 70, which is in series with the previously described float valve 52 to control the water flow into the vent condenser 53, is of the solenoid type controlled by an electric circuit, the valve being open when the circuit is energized and being closed when the circuit is deenergized.

A pair of wires 71 supply current to an electric timer 72, and wires 73, 74, and 75 complete the circuit with the solenoid valve 70 in series with a mercury switch 76. The mercury switch 73 is on a rocker arm 77 of the float control mechanism actuated by the float 61 and closes whenever the float drops in response to demand for new make-up water. Thus the valve 70 is intermittently operated during any period in which the float control valve 52 is open. It is apparent that the float control valve 52 may be omitted entirely if desired.

The timer 72 is of a well known type that is manually adjustable to divide a fifteen-second time period into two parts in any desired proportion. For example, the timer may, in repeated cycles, cause the solenoid of the valve 70 to be energized for 10 seconds and deenergized for 5 seconds.

The panel board 13 may be provided with various instrumentalities. For example, the panel board in Fig. 1 may have the following instrumentalities.

A dial 87 shows the temperature of the feed-water and a dial 88 shows the pressure of the feedwater, both values being taken near the connection of the boiler feed line 17 with the master control unit. The dial 90 indicates the deaeration temperature and the dial 91 indicates the deaeration pressure, both values being taken near the thermostatic bulb 43 where the fluid under pressure flows into the spray head 41. Dial 92 shows the return line pressure near the point at which the return line 18 connects with the combined heat exchanger and separator 31. A dial 93 shows the pressure of the make-up water supply taken near the connection of the water supply pipe 15 with the unit. A signal lamp 95 is responsive to the mercury switch 76 to indicate the periods in which the system is taking in new water and a second signal lamp 96 responds to energization of the solenoid valve 70 to indicate the pulsating action created by the make-up water. The previously mentioned timer

72 is placed on the panel board for manual adjustment as desired. A gauge glass 97 indicates the water level in the master control tank and a switch 88 on the panel controls energization of the condensate motor 86.

Operation

The manner in which the steam system operates and is controlled by the described unit may be understood from the foregoing description.

Steam condenses in each one of the steam chests in the pieces of equipment 26 to give up heat to the material in process, but a portion of the steam flows continuously into the return line 18 through the restrictions 28 because of the open communication through the system. In this method of operation, the flow velocity is substantially higher than the overall or average velocity in a conventional trap system, and the small proportion of steam that is continuously passing through the restrictions 28 effectively carries the condensate out of the steam chests along with noncondensable gases. The drop in pressure at the restrictions 28 causes some of the condensate to flash into steam thereby slightly increasing the steam content of the fluid mixture that reaches the combined heat exchanger and separator 31.

In a steam system having approximately 100 pounds per square inch gauge pressure in the steam header 25, the setting of the thermostatic valve 42 may be, for example, somewhat above 230° F. In any event, the temperature setting of the thermostatic valve will be above the normal temperature prevailing inside the tank 10 but below the normal temperature of steam in the return line 18. If the tank 10 is at 4 to 6 pounds gauge pressure, the temperature therein will be in the range 224°-230° F.

Usually the temperature setting of the thermostatic valve 42 is higher than the steam temperature corresponding to the normal pressure in the receiver tank 10. The thermostatic bulb 43, however, is in the spray head 41 or at least in the passage leading to the spray head where back pressure may be created. The back pressure is sufficient to provide a corresponding steam temperature high enough to cause closing action on a part of the thermostatic valve. In other words, the spray openings restrict flow from the spray head 41 to such an extent that the flow from the thermostatic valve 42 may build up pressure and correspondingly build up temperature in the spray head high enough to affect the operation of the thermostatic valve 42.

In various practices of the invention, the thermostatic valve 42 may completely close or nearly close in response to rising temperature and may be either a quick-acting valve or a stage-acting valve.

If a snap-acting thermostatic valve 42 is employed, it will, in the absence of flow of make-up water, operate inherently in an intermittent or pulsating manner. Thus when the thermostatic valve 42 closes, the back pressure in the spray head immediately drops with corresponding drop of temperature at the thermostatic bulb 43. The thermostatic bulb cools off in response to this drop in the surrounding temperature and thereby causes the thermostatic valve 42 to open. As soon as the valve 42 opens, however, the back pressure and temperature in the spray head 41 again build up to heat the thermostatic bulb 43 and thereby close the valve. In this way, the

thermostatic valve, acting independently of the make-up water supply, opens periodically in an automatic manner to maintain a desired minimum average flow velocity in the system.

Whenever new make-up water is acquired the float 61 lowers to open the water valve 52 and at the same time the mercury switch 78 tilts to close a circuit through the solenoid valve 70 and timer 72. As long as the float 61 is in its lower position, the solenoid valve 70 opens intermittently to release pulses of make-up water for flow through the vent condenser 53 and pipe 55 into the two-stage heater-mixer 40.

Each pulse of water causes the thermostatic bulb 43 to be cooled thereby to open the thermostatic valve 42 for the release of steam from the system. In the usual method of operation, the mixture of steam and water is too low in temperature to cause the thermostatic valve 42 to close so long as cold water continues to flow through the solenoid valve 70. As soon, however, as a pulse of water from the solenoid valve 70 terminates, the steam or steam and condensate from the thermostatic valve 42 raises the temperature in the spray head to cause the thermostatic valve to close.

It is apparent that the described thermostatic arrangement causes the release valve 42 to operate inherently in an intermittent or pulsating manner when no make-up water is flowing. On the other hand, when make-up water is flowing, the flow is broken up into pulses by the solenoid valve 70 and the pulses of water cause corresponding pulsating action on the part of the thermostatic valve 42.

The admission of steam from the return line into the receiver tank 10 substantially concurrent with the admission of make-up water causes the make-up water to be heated to a temperature substantially above 212° F. and places the heated make-up water under considerable pressure in the spray head 41. When this high-temperature high-pressure water is released from the spray head 41 into the lower pressure of the receiver tank 10, a substantial portion of the heated water flashes into steam in an instantaneous manner. This flashing action causes each spray droplet to be shattered with consequent release and separation of the noncondensable gases. The de-aerated water drops to the bottom of the tank 10 while the released noncondensable gases flow upward to the vent 21. The vent condenser 53 not only condenses any steam that may tend to escape but also reclaims heat from the separated gases.

If the thermostatic valve 42 is of the stage-operating type, as distinguished from the above-described snap-acting type, it will continuously seek an equilibrium position in accordance with its temperature setting. In the absence of the flow of make-up water, the equilibrium position of the valve will admit fluid from the return line of the system into the receiver tank 10 at a rate to maintain a pressure and consequent temperature in the spray head 41 corresponding to the temperature setting of the thermostatic valve. When make-up water is demanded, the effect of each pulse of make-up water released by the solenoid valve 70 is to cause the valve to open wider. Thus with a stage-operating valve flow tends to be constant at some minimum level in the absence of make-up water flow, and when make-up water flows the thermostatic valve will operate in a pulsating manner by virtue of the water pulses released by the solenoid valve 70.

A special advantage of this adjustable arrangement for breaking the make-up water flow into pulses is that the rate at which new water is supplied and deaerated may be more or less independent of the action of the boiler feed pump 67. For example, the boiler feed pump 67 may, in a given installation, operate for five minutes and then remain idle for 20 minutes. During the five minutes of pump operation the water level of the reserve body of make-up water 60 in the tank 10 will drop several inches. During the following 20 minutes in which the pump is idle, the solenoid valve 10 will release pulses of water into the receiver to restore the water level.

The timer 12 may, if desired, be so adjusted that the time taken for the water level to be restored is approximately 20 minutes. Thus the new water is sent through the deaeration process gradually, notwithstanding the periodic abrupt drops in the water level inside the tank 10.

Since the master control responds to demand for new water at the boiler end of the system and in doing so speeds up velocity at the return end of the system, the unit may be said to tie the two ends of the system together functionally. The result is a closed chain of causes in which the demand of the boiler for a pound of water to replace a pound of steam consumed in the system causes enough velocity to be created to sweep out the resulting condensate from the steam chests in the system.

Each time the valve 42 opens it causes two things to happen. It causes a pressure pulsation or slight pressure drop in every steam chest in the system, and it causes velocity in the whole system to speed up. In other words, each opening movement of the valve 42 causes a pressure pulsation in each piece of equipment and at the same time causes a strong surge of flow from the equipment through the return line of the system. The pressure pulsations in effect attack the non-condensable gas films in the steam chests because each pressure drop causes a portion of every particle of water in the steam chests to flash into steam in an instantaneous manner. There are countless particles in and near the gas films, and at 100 pounds pressure per square inch the condensate that flashes into steam increases in volume over 240 times. As a result, each particle of water becomes an explosive center of turbulence to disrupt the gas films and to promote heat transfer to the material in process.

The gases torn away from the gas films are quickly picked up by the velocity surges and swept into and through the return line of the system. The velocity surges also sweep condensate out of the steam chests continuously and keep the condensate films exceedingly thin.

Normally, the receiver tank 10 has therein a cloud of steam created by the described deaeration process, which steam accounts for the pressure in the receiver tank being normally a few pounds above atmospheric pressure. When new water released by the solenoid valve 10 flows into and through the vent condenser 53 inside the receiver tank 10, the resultant condensing action on the cloud of steam in the tank lowers the pressure and temperature in the tank. This action has a certain effect on the thermostatic bulb 43 since a pressure drop inside the tank tends to create a pressure drop inside the spray head 41. Thus the flow of water into the vent condenser 53 considered apart from all other concurrent actions tends to cool the thermostatic bulb 43 for opening action by the thermostatic valve 42.

Only water of exceptionally high temperature is fed to the boiler 23 because the condensate returned through the pump 35 is held at high pressure and because all new water added to the system is first preheated at low pressure, then heated at high pressure, and finally intermixed with condensate. The first stage of heating the new water is in the vent condenser 53; the next two stages are in the two-stage heater 40; and the fourth stage with the water under pressure from the pump 67 is accomplished by the coils 68 in the combined heat exchanger and separator 31. In a system using steam at about 100 pounds gauge pressure, final mixture of feed water reaching the boiler is above 300° F. and often around 330° F.

The arrangement shown in Fig. 2, however, has several provisions for promoting flow in cooperation with the thermostatic release valve 42. In the first place, the cooling effect of the vent condenser 53 reduces the pressure and temperature inside the tank with consequent cooling action on the thermostatic bulb 43. In the second place, the continuous removal of condensate by the pump 35 from the lower end of the separator 31 creates flow in the return line 18. In the third place, the exchange of heat for condensing of steam in the separator 31 by the cooling effect of the water coil 68 and/or the cooling effect of water introduced by the spray head 104 serves to promote flow by contraction of the fluid mixture in the end of the return line.

All of these factors working together create and maintain whatever flow velocity is desired in any particular steam system. But it is not necessary in every instance to employ all of the above-mentioned actions to supplement the action of the release valve. Thus the required flow velocity for a steam system may be had by combining the action of the vent condenser 53 alone with the action of the thermostatic valve, or by combining the direct return of condensate alone with the action of the thermostatic valve, or by combining the condensing action in the return line alone with the action of the thermostatic valve, or by combining all or any two of these three supplementary actions with the action of the thermostatic valve.

A special advantage of pumping feed water through the heat exchanger coil 68 is that the water in the coil 68 is under high pressure and is therefore capable of absorbing more B. t. u.'s from the return line than would otherwise be possible. This arrangement which raises the steam-condensing capacity of a given quantity of the make-up water to the maximum is especially valuable in a steam system having a relatively low make-up water demand.

Although opening the thermostatic valve 42 to create velocity may tend to lower the pressure of the condensate delivered to the condensate pump 35, the valve opens only intermittently so that such tendency to drop pressure can occur only intermittently.

65 Tuning the unit to suit a particular steam system

A feature of the invention is that it incorporates a number of elements that may be changed or adjusted to cause the master control unit to match precisely the requirements of any steam system within a very wide range. As a result, the control unit is extremely flexible and is not only readily adaptable to the requirements of any particular system but is also adaptable to changes in a steam system such as the addition 75 of new heating equipment.

11

Any of the following adjustments may be made to vary the operation and control characteristics of the unit:

1. The temperature adjustment 45 of the thermostatic valve 42 may be varied.
2. The rate of supply of the new water may be varied to change the cooling effect of the new water on the thermostatic bulb 43. For example, the float valve 52 may be restricted or limited in its opening action to any degree desired.
3. The closing action of the thermostatic valve 42 as well as the opening action may be limited to any degree desired.
4. The discharge capacity of the spray head 41 may be varied to regulate the manner and degree of pressure rise in the spray head.
5. The prevailing pressure in the master control tank may be raised or lowered.
6. The proportion of make-up water diverted to the spray head 104 in the separator 31 may be varied by the manipulation of the valves 105 and 106.
7. The duration of the water pulses controlled by the solenoid valve 70 may be varied by adjustment of the timer.

If desired, the master control unit may be operated with the valve 37 closed and the condensate pump 35 de-energized. In that event, all of the returns from the system will be discharged through the thermostatic release valve 42 into the receiver tank 10. To make sure that the valve 110 releases the volume of fluid required for this kind of operation, it may be necessary to change the temperature adjustment 45 of the thermostatic valve to a higher setting. In some situations it may be decided to make this kind of operation standard practice. In any event, the method of operation can be used temporarily any time it is necessary to service or repair the pump 35.

Description of Fig. 3

The modification of the invention illustrated in Fig. 3 is largely similar to the previously described arrangement in Fig. 2, as indicated by the use of corresponding numerals to indicate corresponding parts. The general purpose of this figure is to illustrate the fact that the thermostatic release valve 42 may be replaced by various valves of other types.

In this particular instance the thermostatic release valve is replaced by a solenoid release valve 110 that is adapted to be operated either by a timer 111 or a timer 112, both timers being similar to the previously described timer 72.

The timer 111 is energized by a pair of leads 113 and 115 under the control of the mercury switch 76 that closes when the float 61 drops. A pair of wires 116 lead from the timer 111 to the solenoid valve 70 that controls the introduction of new water, and a second pair of wires 117 lead from the timer 111 to the solenoid release valve 110. Whenever the float 61 drops in response to the boiler's requirement for make-up water, the timer 111 is automatically energized by the mercury switch 76 to open the two solenoid valves 70 and 110 intermittently in unison.

The second timer 112 is also energized by the leads 113 and 115 but is under the control of a relay 120 that is in parallel with the timer 111 to be energized simultaneously with the timer 111. This second timer 112 is connected by a pair of wires 121 to the previously mentioned wires 117 that control the solenoid release valve 110.

The operation of this modified form of inven-

12

tion may be readily understood. The adjustment of the timer 111 determines the duration of the short periods in which new water is introduced into the master control unit and causes steam to be released by the valve 110 in synchronization with the water flow. As long as the float 61 is in its lower position, the relay 120 keeps the second timer 112 de-energized. Whenever the float rises to its upper position, however, the relay 120 is de-energized and automatically closes the circuit to energize the second timer 112, whereupon the second timer intermittently opens the release valve 110.

It is apparent that the timer 111 may be readily adjusted in accord with the specific make-up water requirement of a particular steam system so as to spread out the flow of new water to whatever extent may be desired. On the other hand, the timer 112 may be adjusted to determine the release of fluid from the return line of the system when make-up water is not required. This second timer 112 will, of course, be adjusted to maintain whatever minimum velocity in the system is needed between the periods of make-up water demand.

Our description in detail of preferred practices of the invention for the purposes of disclosure and to illustrate the principles involved will suggest to those skilled in the art various changes and substitutions under our basic concepts. We reserve the right to all such departures from our disclosure that fall within the scope of our appended claims.

We claim as our invention:

1. In a steam system having a boiler, at least one steam-using device connected to the boiler, and a return line connecting the steam-using device to the boiler and closed to the outer atmosphere, said device and return line forming a clear channel from said boiler for flow-promoting pressure communication through the system, the combination therewith of: a condensate pump in the return line for returning condensate to said boiler under pressure, said pump having its intake port in direct communication with said return line to promote flow of steam through the steam-using device, and a valve to release fluids from said return line into a region of substantially lower pressure than the return line to set up a pressure differential across the system for additional promotion of flow in the steam system.

2. A steam system as set forth in claim 1, which includes means to open and close said release valve intermittently to create pressure pulsations in said system.

3. In a steam system having a boiler, at least one steam-using device connected to the boiler, and a return line connecting the steam-using device to the boiler and closed to the outer atmosphere, said device and return line forming a clear channel from said boiler for flow-promoting pressure communication through the system, the combination therewith of: a valve to release fluid from said return line into a region of substantially lower pressure than the return line to set up a pressure differential across the system for promoting flow of steam through the steam-using device, and means operatively connected with the return line to bring cooling fluid into heat exchange relation with the contents of said return line for causing condensation of steam therein to create a further pressure differential for further promotion of flow in the system.

4. A steam system as set forth in claim 3, which includes means to open and close said release

valve intermittently to cause pulsations in the system.

5. In a steam system having a boiler, at least one steam-using device connected to the boiler, and a return line connecting the steam-using device to the boiler and closed to the outer atmosphere, said device and return line forming a clear channel from said boiler for flow-promoting pressure communication through the system, the combination therewith of: means to bring cooling fluid into heat-exchange relation with the contents of said return line for causing condensation of steam therein to set up a pressure differential across the system for promotion of flow of steam through the steam-using device, a condensate pump in the return line for returning condensate to said boiler, said condensate pump having its intake port in direct communication with said return line to remove condensate therefrom for further promotion of flow in the system, and a valve to release fluid from said return line into a region of substantially lower pressure than the return line to set up a further pressure differential across the system for still further promotion of flow in the steam system.

6. A steam system as set forth in claim 5, which includes means to open and close said valve intermittently to create pulsations in the system.

7. In a steam system having a boiler, at least one steam-using device connected to the boiler, and a return line connecting the steam-using device to the boiler and closed to the outer atmosphere, said device and return line forming a clear channel from said boiler for flow-promoting pressure communication through the system, the combination therewith of: a separator in said return line for separating steam and condensate, a condensate pump in the return line for returning condensate to said boiler under pressure, said pump having its intake port directly connected to said separator to promote flow in the system, and a valve connected with said separator to release steam therefrom into a region of substantially lower pressure than the return line to set up a pressure differential across the system for additional promotion of flow in the steam system.

8. In a steam system having a boiler, at least one steam-using device connected to the boiler, and a return line connecting the steam-using device to the boiler and closed to the outer atmosphere, said device and return line forming a clear channel from said boiler for flow-promoting pressure communication through the system, the combination therewith of: means operatively connected with the return line to bring cooling fluid into heat exchange relation with the contents of said return line for causing condensation of steam therein to set up a pressure differential across the system for promotion of flow in the system, a separator in said return line for separating steam and condensate, a condensate pump in the return line for returning condensate to said boiler, said condensate pump having its intake port in direct communication with said separator to remove condensate therefrom for further promotion of flow in the system, and a valve to release fluid from said separator into a region of substantially lower pressure than the return line to set up a further pressure differential across the system for still further promotion of flow in the steam system.

9. In a steam system having a boiler, at least one steam-using device, and a return line, said device and return line forming a clear channel

from said boiler for flow-promoting pressure communication through the system, the combination therewith of: a condensate pump for returning condensate to said boiler under pressure, said pump having its intake port in communication with said return line to promote flow in the system, a first electrically controlled valve to release fluids from said return line into a region of substantially lower pressure than the return line to set up a pressure differential across the system for additional promotion of flow in the steam system, a second electrically controlled valve to release make-up water for mixture with the fluid released by said first valve, a first timer to operate said two valves together intermittently, a second timer to operate said second valve intermittently, and means to energize the first timer when the steam system requires make-up water and alternately to energize the second timer when make-up water is received.

10. In a steam system having a boiler, at least one steam-using device, and a return line, said device and return line forming a clear channel from said boiler for flow-promoting pressure communication through the system, the combination therewith of: a separator in said return line, a heat-exchange passage in said separator to bring cooling fluid into heat-exchange relation with the contents thereof for causing condensation of steam therein to set up a pressure differential across the system for promotion of flow in the system, a condensate pump for returning condensate to said boiler, said condensate pump having its intake port in a communication with said separator to remove condensate therefrom for further promotion of flow in the system, and a valve to release fluid from said separator into a region of substantially lower pressure than the return line to set up a further pressure differential across the system for still further promotion of flow in the steam system.

11. A steam system as set forth in claim 10, which includes means to open and close said valve intermittently to create pulsations in the system.

12. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure than the return line to set up a pressure differential across the system for promoting flow in the steam system, means to use said released fluid to preheat make-up water, and means to bring the preheated water into heat-exchange relation with the contents of said return line for causing condensation of steam therein to create a further pressure differential for further promotion of flow in the system.

13. In a steam system having a boiler, at least one steam-using device, and a return line, said device and return line forming a clear channel from said boiler for flow-promoting pressure communication through the system, the combination therewith of: means to bring make-up water into heat-exchange relation with the contents of said return line for causing condensation of steam therein to create a further pressure differential for further promotion of flow in the system, and means to raise the pressure of said make-up water to increase the capacity of the water to absorb heat from said return line without vaporizing.

14. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure than the return line to set up a pressure differential across the system for promoting flow in the steam system, means to use said released fluid to preheat make-up water, means to raise the pressure of said preheated make-up water to increase its capacity for absorbing heat without vaporizing, and means to bring the preheated and pressurized water into heat-exchange relation with the contents of said return line for

causing condensate of steam therein to create a further pressure differential for further promotion of flow in the system.
